BEER DISPENSER AND COOLER

Frank R. Lueck, Milwaukee, Wis., assignor to The Central Brass Mfg. Company, Cleveland, Ohio, a corporation of Ohio

Application February 8, 1934, Serial No. 710,274

6 Claims. (Cl. 225—3)

This invention relates to beer dispensers and particularly to coolers therefor.

An object of the present invention is the provision of a simple and inexpensive beer dispensing cooler which may be readily structurally combined with present commercial forms of tapping equipment so as to provide a convenient means for the dispensing of draft beer at palatable temperatures.

10 The cooler of the present invention is particularly adapted for home, club, picnic, or other uses where bar facilities are not available for the serving of draft beer.

15 Other more specific objects and advantages will appear, either expressed or implied, from the following description of a beer dispensing cooler constructed in accordance with the present invention.

20 The single figure of the accompanying drawing is a vertical sectional view of a dispensing cooler embodying this invention, showing the same applied to a conventional tap rod.

25 The dispensing cooler shown comprises an ice receptacle 10 of appropriate form having a length of beer conducting tubing 11 therein. By arranging the tubing in the form of a coil adjacent the side walls of the receptacle, a maximum length of tubing may be employed without unduly limiting the ice receiving capacity of the 30 receptacle.

The receptacle 10 is shown applied to the projecting end of a conventional tap rod 12, which extends upwardly from the contents of the barrel 13 through a conventional tap 14, releasably secured to the barrel in a well known manner.

35 In this instance the receptacle 10 is fixed at its bottom 16 to a supporting column or post 15 which extends upwardly therethrough into a cross member 17 secured to and spanning the top 40 of the receptacle. The post 15 is hollowed out, as at 18, to telescopically receive the end of the tap rod 12, and is provided with an appropriate packing gland 19, which serves to releasably secure the post 15 to the rod 12 and to provide a 45 fluid tight joint therebetween.

45 The channel 18 in the post 15 is connected to one end 20 of the tubing 11 through a union 21 applied to a nipple 22 on the post, and the other end 23 of the tubing is similarly connected to a 50 separate channel 24 in the upper end of the post, through a union 25 and nipple 26. The channel 24 communicates with an appropriate faucet 27 through which the beer is dispensed, the faucet being mounted preferably upon the upper 55 reduced end 28 of the post.

It will thus be noted that in the device shown the post 15 constitutes a support for the receptacle 10, the tubing 11, and the faucet 27; it also provides a simple and convenient mounting means by which those parts may be readily applied, as a unit, to the tap rod 12; and it also serves to conduct the beer from the rod 12 to the tubing 11 and from the tubing to the faucet 27. In its passage through the tubing 11 the beer is chilled by the ice in the receptacle and discharges 10 through the faucet at a palatable temperature.

Various changes may be made in the invention hereinabove specifically described without departing from or sacrificing the advantages of the invention as defined in the appended claims. 15

I claim:—

1. In a dispensing cooler the combination of a tap for application to a barrel, a tap rod supported by the tap, a receptacle for receiving a cooling medium, a coil of tubing in said receptacle for conducting a beverage therethrough, means for mounting said receptacle on the tap rod for support thereby, said mounting means including means for establishing communication between the tap rod and one end of said tubing 20 by application of said mounting means to the conduit, and a faucet communicating with the other end of said tubing. 25

2. A dispensing cooler comprising a tap applied to a beverage supply barrel, a tap rod supported by the tap, a receptacle for receiving a cooling medium, a coil of tubing in the receptacle for conducting the beverage therethrough, a receptacle support having a channel to receive the tap rod, releasable means for effecting a tight 30 connection between the support and the tap rod, means connecting one end of the tubing to the channel, and a faucet connected with the other end of the tubing. 35

3. In a dispensing cooler for application to an 40 upstanding beverage conduit, the combination of an elongated hollow member for connection with the conduit, conduit-engaging means upon the member securing the member to the conduit to thereby support the member, a receptacle for a 45 refrigerant surrounding the member and supported thereby, a coil of tubing in the receptacle having one end communicating with the hollow member, and a faucet communicating with the other end of the tubing. 50

4. A dispensing cooler comprising an ice receptacle, a beverage conduit therein, a faucet carried by said receptacle, and an elongated hollow member having two separate longitudinal channels formed therein, one of said channels being 55

connected with one end of said conduit, and the other of said channels being connected with the other end of said conduit and with said faucet.

5. In a dispensing cooler for removable application to a beverage supply conduit, the combination of a receptacle for receiving a cooling medium, an upright post in said receptacle having a channel to receive the conduit, releasable means for effecting a tight connection between 10 said post and conduit, a faucet, said post having a second channel communicating with said faucet, and a coil of tubing in said receptacle with its opposite ends communicating respectively with said channels.

6. A dispensing cooler for application to an upstanding beverage conduit, comprising a receptacle for a refrigerant, an upstanding elongated member passing through the receptacle and in supporting engagement with the bottom of the receptacle, a brace connecting the top of the receptacle to the member, means for mounting the member upon the conduit to thereby support the receptacle, a channel in the member communicating with the conduit, a coil of tubing within the receptacle communicating at one end with the channel, and a faucet communicating with the other end of the tubing. 5 10
